UNITED STATES PATENT OFFICE.

TOREY ROSS, OF CHICAGO, ILLINOIS.

TIME RECORDER.

Application filed April 1, 1921. Serial No. 457,762.

To all whom it may concern:

Be it known that I, TOREY ROSS, a citizen of the United States of America, and a resident of Chicago, county of Cook, and State of Illinois, have invented certain new and useful improvements in Time Recorders, of which the following is a specification.

My invention relates to time recorders of the type illustrated in my Patent No. 1,262,703, dated April 16, 1918, and has for its object improvements in the driving and setting mechanisms of such recorders.

In the accompanying drawings—

Fig. 1 is a rear elevation of the left hand end of the machine as viewed from the rear, said parts of the machine including all of the present invention;

Fig. 2 is a section on line 2—2 of Fig. 1;

Fig. 3 is a plan, the same being a section 20 on line 3—3 of Fig. 2;

Fig. 4 is a section on line 4—4 of Fig. 2; and

Fig. 5 is a detail at reduced size of some of the parts shown in Fig. 2.

In Figs. 1 and 5, the parts are shown in one position in full lines, and in their alternative position in dotted lines.

The parts of the machine herein involved lie principally between the standards 10 and 11 of the recorder. The main shaft of the machine is shown at 12, and the present invention concerns itself with the driving and setting of that shaft.

Mounted upon the standards 10 and 11 is a piece of insulation 13, and secured to the under face of this is a magnet 14. Pivoted on a rod 15 in the lower part of the apparatus is a channel 16, and secured in this channel is a bracket 17. Mounted upon 40 the bracket 17 is another magnet 18, the pole 19 of which is closely adjacent to the pole 20 of magnet 14. Electrical connections for the magnets are shown at 21 and 22.

The parts are so arranged that when an electrical impulse is sent thru the two magnets, their poles attract each other, and the lower magnet with its supporting parts is moved on the pivot 15 from the full line to 50 the dotted line position shown in Fig. 2. When the circuit is broken thru the magnets, the moved parts fall back by gravity to their normal position.

An extended part of the channel 16 is in 55 the form of an arm 23 having its upper end 24 bent over in a convenient form to strike

the teeth of a star wheel 25 fast on shaft 12. Pivoted to the channel 16 at 26 is another arm 27 which has its upper end 28 similarly bent over to strike the teeth of the 60 star wheel 25. A spring 50 holds arm 27 against a projection 51 on arm 23, so that normally arms 23 and 27 act as if they were rigidly secured together. In addition to the gravity action before mentioned as 65 acting on the magnet 18 and channel 16, there is a spring 29 connected to arm 23 and acting to pull said arm and associated parts downward. This normally keeps the end 28 of arm 27 in engagement with a 70 tooth of the star wheel, and end 24 of arm 23 out of such engagement.

Pivoted at 30 on the frame is a pawl 31 which normally rests on the tip of one tooth of the star wheel. At 32 on opposite sides 75 of the pawl arm are pins secured in the frame of the apparatus. These pins are for the purpose of limiting the movement of the pawl 31 to as short a throw as will serve the purpose. When the star wheel is advanced in a contra-clockwise direction, as shown in Fig. 2, a tooth slips from under the pawl, and said pawl drops to rest on the lower pin 32. This is not a drop to the full depth of the tooth, but only enough to 85 prevent a reverse movement of the wheel 25. In the standing position shown in Fig. 2, the end of the star wheel tooth which is under the pawl is very close to the end of the pawl so that a very short advance of 90 the wheel permits the pawl to drop into its lower position.

The circuit for the magnets 14 and 18 is connected to a master clock or to some other means by which said circuit is closed once 95 each minute and immediately thereafter is broken. When the circuit is closed, the magnet 18 is raised as before described, and this causes the end 24 of arm 23 to strike one tooth of the wheel 25 and come to rest 100 in the crotch between two teeth. This advances the wheel a small part of the distance between one tooth and the next, which advance is sufficient to permit the pawl 31 to drop behind the tooth on which it was 105 previously supported.

When the circuit is broken thru the magnets, the arm 23 drops and causes the end 28 of arm 27 to strike a tooth which was advanced into its path by the previous 110 action of arm 23. This advances the star wheel the remainder, and main part, of the

distance between one tooth and the next. The lower and normal position of the magnet 18 is determined by the end 28 coming to rest in the crotch between two teeth on the star wheel. When another impulse flows thru the magnets, the ratchet wheel will be advanced another step, and so on.

On the end of shaft 12 is a bevel gear 33 which engages another bevel gear 34 on shaft 35. The upper end of shaft 35 is connected thru a train of gearing 36 with a clock hand 37 which moves over a clock dial 38. The hand 37 is the minute hand of the clock and advances one step each time that the magnet 18 moves to its attracted position.

Pivoted at 39 on the frame work of the machine is a lever which has arms 40, 41, 42, 43 and 44. The arm 40 is a weighted arm which normally holds the lever with arm 42 in contact with a shaft 45 which is part of the machine but which is only a stop as far as present matters are concerned. The arm 41 has thereon a finger piece 46 by which the lever may be manually moved to an extent which will bring arm 41 against stop 45. When so moved the curved face 47 on the lower end of arm 43 passes over the end 24 of arm 23 and holds such arm from being moved to engagement with the teeth of star wheel 25. Immediately after the curved face 47 first passes over end 24, the arm 44 strikes the end 28 of arm 27 to move said arm on its pivot 26 against the tension of spring 50 until the end 28 is entirely clear of the teeth of star wheel 25. In this condition the clock may be set by manually moving the hand 37 forward, which is the direction on the star wheel which the pawl 31 permits it to move.

The operations just described serve to set the clock mechanism, and consequently the shaft 12 which is connected thereto by gearing. The release of the arm 41 permits arm

27 to return to engagement with projections 51 under action of spring 50. In this condition, impulses thru magnets 14 and 18 advance the mechanism step by step. The ends 24 and 28 are so related to each other that one or the other is always within the diameter of wheel 25 when operated by the magnets.

What I claim is:

1. In a mechanism of the class described, a pivoted arm, a second arm pivoted to the first one, a spring acting to draw the two arms toward each other, a stop on one of the arms for limiting the scope of the spring action, a wheel, means for moving the arms on the pivot of the first one for driving the wheel, and means for moving the second arm on the interconnecting pivot to free both arms from said wheel.

2. In a time recorder, the combination with a shaft, a star wheel secured thereon, and a clock mechanism geared to said shaft, of a pivoted lever having two arms arranged to engage said wheel alternately when said lever is vibrated on its pivot, means for vibrating said lever to drive said shaft, and a manually operated device for spreading said arms so as to simultaneously free both arms from said wheel.

3. In a mechanism of the class described, a wheel and a pallet for driving it, said pallet having one arm normally free from said wheel, and a device for holding said arm in its normal position and at the same time moving the other arm so as to free it from the wheel.

4. In a clock driving mechanism, a wheel, a pallet, and a magnet for operating said pallet to drive said wheel, said magnet being mounted upon said pallet so that magnetism serves to move the pallet in one direction and the weight of the magnet serves to move it in the other direction.

TOREY ROSS.
